TOILET FLUSH VALVE CONTROL

Benjamin T. Ezzell, Harlingen, Tex.

Application August 12, 1955, Serial No. 527,924

2 Claims. (Cl. 4—53)

This invention relates to flushing mechanisms for toilets. More particularly, the invention has reference to a generally improved flush valve, of improved design, together with a means for automatically controlling the operation of the same during flushing of the toilet.

Conventional flush ball valves have certain deficiencies in operation. For example, a valve of this type often drops too soon, during flushing of the toilet, and as a result, as substantial part of the water within the flush tank is not flushed into the bowl. In other instances, the ball valve does not seat properly, and care must be taken to maintain the same in such a position as to cause it to drop in true vertical alignment with its associated valve seat, else the valve will not seat properly and continued flushing will result.

Still further, in conventional flushing mechanisms of the type referred to, rather frequent replacement of the ball valve is required, due to its formation from relatively soft rubber material. In most instances, this is not only an expense to the householder, but also an inconvenience as regards the necessity of replacing the worn valve.

The main object of the present invention is to provide a generally improved flush valve for toilets, which will be so designed as to insure that the valve will drop to a closed position at a predetermined time during flushing of the toilet with a minimum deviation from the exact time at which it is to drop.

Another object is to provide a valve which will have associated therewith a notch and pawl means, with the pawl means fully controlled in such a manner as to insure that the valve will be held in its upper position, to permit exhaustion of the flush tank contents into the toilet bowl, despite substantial turbulence in the area of the flush valve.

Another object of the invention is to provide a valve as described in which the notch and pawl engagement will be maintained as long as there is water in the area surrounding the notch and pawl means, with the dropping of the water level below said notch and pawl being automatically operative to effect engagement of the valve, to cause the same to seat immediately.

Another object is to associate with the valve a counter-weight means which cooperates with the float-controlled notched means in assuring that the valve will be kept in its upper position while the flushing operation is taking place, said counterweight means being so designed as to, in the absence of water surrounding the same, assert a substantial pressure on the valve means effective to cause the same to be immediately seated.

Another object is to provide a device as stated which will be adapted for use with wholly conventional flush tank and flushing mechanism components.

Other objects will appear from the following description, the claims appended thereto, and from the annexed drawing, in which like reference characters designate like parts throughout the several views, and wherein:

2

Figure 1 is a fragmentary vertical sectional view through the lower portion of a toilet flush tank, showing therein a valve according to the present invention in closed position;

5 Figure 2 is an enlarged sectional view on line 2—2 of Figure 1;

Figure 3 is a transverse sectional view on line 3—3 of Figure 2; and

10 Figure 4 is a fragmentary view similar to Figure 1 in which the valve is in open position.

The reference numeral 10 generally designates a conventional toilet flush tank, having a bottom wall 12 and a side wall 14. Designated at 16 is a conventional valve seat, having integral therewith a laterally projecting conduit 18 receiving the lower end of the vertical overflow pipe 20.

20 Gripping the overflow pipe 20 are semi-circular, complementary clamp sections 22, 24 having outwardly projecting ears formed with registering openings receiving clamping screws 26. One of the clamp sections is integrally formed with a laterally outwardly projecting bracket 28 having an upwardly extending free end portion 29 formed with an upwardly opening guide slot 30, in which is vertically swingable a float arm 32 to the outer end of which is secured a float 34. Arm 32 at its inner end is pivoted upon a lug 36 on and projecting laterally from the clamp section 24 for swinging movement in a vertical plane. Integrally formed upon the arm 32, adjacent the pivot axis thereof, is an upwardly projecting hook terminating at its upper end in a pawl 38 which projects toward the lug 36.

25 A U-shaped yoke 40, disposed at the opposite side of the pipe 20 from the float arm 32, has its legs located at opposite sides of the clamp structure. The free ends of the legs of the yoke 40 are journaled on horizontally aligned trunnions 42 on the related clamp sections, pivotally mounted the yoke for swinging movement in a vertical plane about an axis spaced above and paralleling that of the float arm 32. One of the yoke legs has at its free end an upwardly open notch 44, in which the pawl 38 is adapted to engage in the manner shown in Figure 4.

30 Projecting from the bight portion the yoke 40 in a direction away from the float arm 32 and in the plane of the yoke 40, in an elongated horizontally disposed extension 46 having intermediate its ends a depending lug 47 which is connected by a screw 48 (see Figure 3) to the center portion of a flat flush valve 50. The flush valve 50 is preferably formed of a thick disc 51 of relatively soft resilient material such as rubber. Reinforcing the marginal portion of the valve disc 51 is a ring 52 formed of plastic or the like, which is bonded to the upper side of the disc 51.

35 Secured to the extension 46 at the location of the lug 47 is a counterweight arm 54, in the form of a vertically elongated, obtusely angulated rod. In the closed position of the valve 50 the arm 54 inclines laterally from the extension and toward the pipe 20. Secured fixedly to the upper end of the arm 54 is an oval counterweight 56.

40 The free end of the extension 46 remote from the yoke is integrally formed with an upwardly projecting finger 58, to whose upper end is connected the lower end of a chain 60. The chain 60 is arranged to be pulled upwardly by a conventional manual flush tank lever (not shown).

45 In the closed condition of the device, the parts are as shown in Figure 1, the float arm 32 being horizontally disposed, as is the yoke 40, and the valve 50 firmly seated against the seat 16. The pawl 38 is disengaged from the notch 44 and is out of contact with the adjacent rounded end 45 of the adjacent yoke arm. The weight of the

counterweight 56 is so distributed as to exert a strong downward pressure on the flush valve 50, tending to hold the same seated.

When the toilet tank is to be flushed, the chain 60 is pulled upwardly, and this swings the yoke 40 and the valve 50 upwardly to the positions thereof shown in Figure 4. In this connection, it will be understood that as long as the flush tank is filled with water, there is an upward pressure upon the outer end of the float arm 32, by reason of the buoyancy of the completely immersed float 34, which tilts the arm 32 upwardly about the axis of its pivot 36.

When the valve 50 is swung upwardly to the position shown in Figure 4, the notch 44 in the yoke leg engages the pawl 38, so that the yoke 40 is latched in its upwardly swung position, with the counterweight 56 disposed to the left of the yoke pivots 42, so that the flush valve 50 is overbalanced in its open position.

As soon as the water within the flush tank drops to a level below the float 34, said float will be no longer buoyantly supported, and will become a weight causing the arm 32 to swing downwardly from its uptilted position, whereby the pawl 38 becomes disengaged from the notch 44, and the flush valve 50 immediately swings downwardly toward its closed position. It is to be noted in this connection that the suction effect of the outgoing water, which ordinarily exerts a strong effect on the operation of a conventional rubber ball valve, tending to shut such valve prematurely, does not produce such premature closing operation of the instant valve, and neither does the turbulence of the outgoing water, while the pawl 38 is engaged with the notch 44.

It will be noted that the device can be associated with a conventional flush tank structure, the seat 16 and overflow pipe 20 being wholly conventional. By means of the clamp sections, the entire device is mounted in place upon the overflow pipe, and except for minor adjustments of the device in a circumferential direction about the overflow pipe to insure that the valve 50 will be properly centered with respect to the valve seat 16, no further mounting procedures are required.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

I claim:

1. In combination, a toilet flush tank valve seat, a vertical overflow pipe rising alongside of said seat, a clamp surrounding the overflow pipe, a bracket fixed on and positioned at one side of said clamp, a float arm overlying said bracket and horizontally pivoted at one end on said clamp, a float mounted on the opposite end of said float arm, said float arm being arranged to rest upon said bracket in a horizontal position of the float arm, an up-

standing pawl on and intermediate the ends of said float arm, a valve arm having a yoke on one end thereof having legs embracing the overflow pipe and pivoted to opposite sides of said clamp on a level spaced above said float arm pivot, one of the yoke legs being vertically aligned with said float arm, said one yoke leg having an upwardly opening notch, a flush valve on the other end of the valve arm engageable with said valve seat in a horizontal position of the valve arm, said float arm being arranged to occupy an uptilted position while water is in the tank, and said valve arm being arranged to be uptilted from its horizontal position to engage the notch in said one yoke leg with the pawl on the float arm whereby the valve arm is maintained in an uptilted position and the valve is unseated from the valve seat while water drains through the valve seat until the water level in the tank subsides below the float arm and permits the float arm to subside toward its horizontal position and disengages the pawl from the notch of the valve arm yoke leg.

2. In combination, a toilet flush tank valve seat, a vertical overflow pipe rising alongside of said seat, a clamp surrounding the overflow pipe, a bracket fixed on and positioned at one side of said clamp, a float arm overlying said bracket and horizontally pivoted at one end on said clamp, a float mounted on the opposite end of said float arm, said float arm being arranged to rest upon said bracket in a horizontal position of the float arm, an upstanding pawl on and intermediate the ends of said float arm, a valve arm having a yoke on one end thereof having legs embracing the overflow pipe and pivoted to opposite sides of said clamp on a level spaced above said float arm pivot, one of the yoke legs being vertically aligned with said float arm, said one yoke leg having an upwardly opening notch, a flush valve on the other end of the valve arm engageable with said valve seat in a horizontal position of the valve arm, said float arm being arranged to occupy an uptilted position while water is in the tank, and said valve arm being arranged to be uptilted from its horizontal position to engage the notch in said one yoke leg with the pawl on the float arm whereby the valve arm is maintained in an uptilted position and the valve is unseated from the valve seat while water drains through the valve seat until the water level in the tank subsides below the float arm and permits the float arm to subside toward its horizontal position and disengage the pawl from the notch of the valve arm yoke leg, and counterweight means on said float arm reaching across said overflow pipe toward and above said float arm, said counterweight means serving to maintain the yoke leg notch engaged with the float arm pawl until the float arm pawl is disengaged from the notch by subsidence of the float arm.
